DINNER PLATE

Evan K. Shaw, Manhattan Beach, Robert Y. Allen, Pacific Palisades, and Melvin Shaw, Beverly Hills, Calif., and Gisella Loeffler, Taos, N. Mex., assignors to Metlox Mfg. Co., Manhattan Beach, Calif., a corporation of California

Application May 25, 1953, Serial No. 25,174

Term of patent 3½ years

(Cl. D44—15)

The figure is a plan view of a dinner plate showing our new design; part of which is shown in broken lines for convenience of illustration.

The dinner plate is of a conventional appearance when seen in side elevational view.

We claim:

The ornamental design for a dinner plate, as shown and described.
